UNITED STATES PATENT OFFICE.

MOSES C. SWEZEY, OF NEW HAVEN, CONNECTICUT.

DESIGN FOR A CASH-CAR FRAME.

SPECIFICATION forming part of Design No. 27,174, dated June 8, 1897.

Application filed April 24, 1897. Serial No. 633,809. Term of patent 31 years.

To all whom it may concern:

Be it known that I, MOSES C. SWEZEY, of New Haven, in the county of New Haven and State of Connecticut, have invented a new 5 Design for Cash-Car Frames; and I do hereby declare the following, when taken in connection with the accompanying drawing and the letters of reference marked thereon, to be a full, clear, and exact description of the same, 10 and which said drawing constitutes part of this specification and represents a perspective view of a cash-car frame embodying my design.

This invention relates to a design for cash- 15 car frames; and it consists in the configuration as herein shown and described.

My newly-designed cash-car frame is formed with a centrally-arranged depending cylindrical body A, which is surmounted by two 20 corresponding vertically-arranged parallel

flanges B B, which are each formed with a finger B' and with two inwardly-turned scrolls B²B². Extending in opposite directions from a point between the said body and flanges are two long-corresponding arms C C, terminating at their outer ends in vertical uprights C' C', each of which is formed with a deep rounded notch C², all as shown in the accompanying illustration.

I claim—

The design for a cash-car frame as herein shown and described.

In testimony whereof I have signed this specification in the presence of two subscribing witnesses.

MOSES C. SWEZEY.
